US0D1082583S

(12) **United States Design Patent** (10) Patent No.: **US D1,082,583 S**
(45) Date of Patent: ** Jul. 8, 2025

(54) **SENSOR**

(71) Applicant: **Tridonic GmbH & Co KG**, Dornbirn (AT)

(72) Inventors: **Roger Kistler**, Ennenda (CH); **Ennio Mülle**, Schänis (CH)

(**) Term: **15 Years**

(21) Appl. No.: **35/522,329**

(22) Filed: **Aug. 20, 2024**

(80) **Hague Agreement Data**

Int. Filing Date: **Aug. 20, 2024**

Int. Reg. No.: **DM/239860**

Int. Reg. Date: **Aug. 20, 2024**

Int. Reg. Pub. Date: **Sep. 13, 2024**

(30) **Foreign Application Priority Data**

Feb. 22, 2024 (EM) 015051089-0001

(51) LOC (15) Cl. **10-05**

(52) U.S. Cl.

USPC **D10/106.6**

(58) **Field of Classification Search**

USPC D10/49, 75, 106.6, 104.1; D16/203
See application file for complete search history.

Primary Examiner — George D. Kirschbaum

(57) **CLAIM**

The ornamental design for a sensor as shown and described.

DESCRIPTION

1. Sensor

1.1 : Perspective

1.2 : Perspective

1.3 : Back

1.4 : Bottom

1.5 : Top

1.6 : Front

1.7 : Left

1.8 : Right

The figures show different views of a sensor that can be coupled with a luminaire.
